[57] CLAIM

The ornamental design for a nipping tool for plate-like members or the like, substantially as shown.

DESCRIPTION

FIG. 1 is a front, perspective view of a nipping tool for a plate-like member or the like showing my new design; FIG. 2 is a rear, perspective view thereof;

FIG. 3 is a bottom plan view thereof, the top view being a mirror image;

FIG. 4 is a right side, elevational view thereof; and

FIG. 5 is a left side, elevational view thereof.

FIG. 1

FIG. 2

FIG. 3

FIG. 4

FIG. 5
